LOOP ANTENNA

Armig G. Kandoian, New York, N. Y., assignor to
 Federal Telephone and Radio Corporation, a
 corporation of Delaware

Application October 7, 1942, Serial No. 461,148

8 Claims. (Cl. 250—33)

This invention relates to antenna arrangements and more particularly to broad band antenna systems.

Antenna systems have been proposed in which relatively short radiant acting elements are arranged in the form of a closed pattern and energized opposite diagonal ends of the pattern. Such antenna structures and their operation are more fully set forth in the patent of Andrew Alford No. 2,283,897 issued May 26, 1942, entitled "Antenna systems." In this type of antenna it has also been proposed to make the radiant acting members relatively massive and in this way it is not necessary to provide a separate capacitive coupling between the units at the ends where the feeding does not take place.

For operation at relatively wide frequency bands, it is desirable to support the radiant acting members in such a way that the supporting members are not subjected to a voltage stress even when the voltage node shifts from the midpoint of the antenna due to a change in the frequency of the energy supplied at the ends of the radiant acting members.

Furthermore, it is often desirable to arrange two or more of these units in a vertical array in order to sharpen the directivity in a vertical direction. When such an array is made, it is generally necessary to arrange the feeders for supplying the energy to both sets of units.

It is an object of my invention to provide a loop antenna arrangement operating over a broad frequency band and supported in such a manner that voltages are not developed across the supporting members with a shift in the wavelength of the exciting voltage.

It is a further object of my invention to provide a simple feeding system for a vertical array of short wave loop antennae consisting of a plurality of separate radiant acting members arranged in a form of substantially closed pattern.

In accordance with a feature of my invention the radiant acting members are made of hollow conductive material. The feeding lines are connected to one end of each member and the supporting rods which may be of conductive material are fastened directly to the inner surface of the hollow members and insulated from direct contact with the outer surface thereof.

A better understanding of my invention and the objects and features thereof may be had by reference to the accompanying drawing, in which:

Fig. 1 is a top plan view partially in section showing the structural arrangement of an antenna in accordance with my invention;

Fig. 2 is a fragmentary cross-sectional view taken at line 2—2 of Fig. 1; and

Fig. 3 is a perspective view of an antenna array in accordance with my invention.

Turning first to Fig. 1, the antenna is composed of four hollow radiant acting members 1, 2, 3, 4 arranged in the form of a substantially closed pattern. Substantially centrally of the square is provided a feedline provided with a shield 5 which serves as a supporting mast for the antenna structure. Within the shield 5 are provided two parallel transmission line conductors indicated at 6 and 7. These conductors 6 and 7 are connected by branch lines 8, 9 to the ends of closed members 1 and 2 and by means of branch lines 10 and 11 to the diagonally opposite ends of members 3 and 4. Members 1, 2, 3 and 4 all are preferably one half wavelength or less of the operating wave band so that in effect a current loop occurs in each of the members and the effective currents in each of the members are all in the same direction around the periphery of the closed pattern. Each of the members 1, 2, 3 and 4 is preferably made in the form of a semi-cylinder as shown at 20 (Fig. 2) preferably with a metal closure member 21 across the open face of the cylinder. Likewise, each member is preferably provided with an end closure as shown at 12 (Fig. 1).

Such a loop construction has been made with each of the members about ten inches in length and of a semi-cylindrical form of about five inches in diameter. This loop structure was found to operate satisfactorily at frequencies from 300 to 350 megacycles.

However, if the loop is tuned to the mean frequency of this wave band, it is clear that the voltage node, existing in members 1 to 4 inclusive, at this tuned frequency, will shift somewhat to either side, thereof, as the frequency is changed toward the ends of the band. Thus, if the support for each member is connected directly to the outside surface thereof, there will be a voltage developed across this support at all the frequencies except the mean frequency.

In order to avoid this effect, I provide supporting members 14, 15, 16, 17 fastened at one end to a supporting sleeve 18 directly connected to shielded line 5 and at their other end passing through an opening in the closure member 21 to the inner surface of each of the members where they are securely fastened as indicated at 19. Since each radiant acting member is substantially an electrically shielded circuit, there is substantially no voltage within so that no voltage

is developed between points 18 and 19 regardless of shifting of the nodes on the outer surface of the conducting member. Accordingly, supporting members 14 to 17, inclusive, may be made of metal and directly welded to the radiant acting members. By this construction it is possible to make a loop more rigid than would be possible if insulating rods were required as supports. Furthermore, the insulation of the system is greatly improved since there is substantially zero voltage developed at the extreme ends of the supporting rods for all conditions of operation. The use of the metallic supports serves as a lightning protection for the system. It is further pointed out that if insulating supports are used a separate conductor fastened to the inner surface of the antenna members and the mast may be provided for lightning protection.

It is clear, of course, that members 1 to 4, inclusive, may be made in any desired hollow form, the semi-cylindrical form being illustrated since it is a relatively easy form to construct. Likewise, the members may be in other shapes so that the closed pattern may take other forms, for example, a circle.

In Fig. 3 is illustrated two of these antenna units mounted on a common supporting shielded conductor line 30. Connections are made to the opposite diagonal corners of upper unit 31 of the array and from this connection point leads 32 are brought to the corresponding diagonal points of lower unit 33. Preferably, units 31 and 33 are supported about one-half wavelength apart and transpositions 34 are provided in each of lines 32 so that in-phase energization of the two loops may be accomplished. It is clear, however, that if it is desired that the antenna units be operated in phase opposed relation, the transpositions may be omitted.

Furthermore, if it is desired that the spacing be made some other value than half a wavelength, the interconnecting lines 32 may be made of proper length to secure the desired phase relationship of energization.

The antenna array may be connected by means of line 30 to any suitable translating device such as shown at 35.

It is clear that many modifications in the construction of the apparatus described above may be made within the scope of my invention by those skilled in the art. The particular mounting arrangement for avoiding voltage development across the supporting leads may apply to other types of antenna than those specifically shown and described in connection with Figs. 1 and 2.

While I have described the principles of my invention in connection with specific apparatus and particular modifications thereof, it is to be clearly understood that this description is made only by way of example and not as limitations on the scope of my invention as set forth in the objects thereof and in the accompanying claims.

What is claimed is:

1. A radio antenna comprising a hollow radiating element, of a given length means for energizing said radiating element, a conductive supporting mast for said element substantially at right angles thereto, and conductive supporting means substantially at right angles to the lengthwise dimension of said element and said mast, fastened to said mast and fastened to the inner surface of said hollow element.

2. A radio antenna comprising a plurality of hollow radiating elements arranged in a substantially closed pattern, each of said elements hav-

ing a substantially equipotential inner surface means for energizing said radiating elements at their ends, a common conductive supporting mast for said elements extending within said closed pattern, and conductive supporting means for said elements fastened to said mast and fastened to the inner surfaces of said hollow elements.

3. A radio antenna for operating at a wide frequency band comprising a plurality of hollow radiant acting members, each being no longer than substantially one half wavelength at the operating frequencies, said members having substantially equipotential inner surfaces and being arranged in the form of a substantially closed planar pattern, a shielded transmission line substantially normal to said pattern, means for connecting said transmission line to the ends of said members and supporting means for said members fastened at one end to the shield of said transmission line and at their other ends to the inner surface of each of said hollow members.

4. A radio antenna for operating over a wide frequency band comprising four hollow radiant acting members each being no longer than sub-

stantially one half wavelength at the operating frequencies, said members having substantially equipotential inner surfaces and being arranged in the form of a substantially closed planar pattern, a shielded transmission line substantially normal to said pattern, means for connecting said transmission line to the diagonally opposed ends of said members and supporting means for each of said members fastened at one end to the shield of said transmission line and at their other ends to the inner surface of the corresponding one of said hollow members.

5. A radio antenna according to claim 4, further comprising a second set of members fastened to the shield of said transmission line in a manner similar to said first set of members, and feeding connections between the ends of said first set of members connected to said transmission line and the corresponding ends of said members of said second set.

6. A radio antenna according to claim 4 wherein the length of said members are of the order of between $\frac{1}{2}$ and $\frac{1}{6}$ wavelength at the operating frequencies.

7. A radio antenna for operation over a frequency band comprising a hollow radiating element of a given length, means connected to one end of said element for energizing same at a plurality of frequencies within said band whereby there is a shifting with frequency of the voltage node along said element, a conductive supporting mast extending at right angles to said element, and a supporting means extending at right angles to both said element and said mast conductively connecting said element to said mast, the point of connection of said supporting means to said element being inside said element and such as to have a potential which remains substantially unchanged with variation in frequency.

8. A radio antenna for operation over a frequency band comprising a hollow elongated radiating element, means connected to one end of said element for energizing same, a conductive supporting mast at right angles to said element, and a conductive supporting means connecting said mast to said radiating element at a point having substantially the same potential as said mast, said supporting means extending at right angles to both said mast and said element.
